UNITED STATES PATENT OFFICE.

EDWARD H. PALMER, OF DETROIT, MICHIGAN.

COMBINING AND MIXING TUBE.

No. 872,580.

Specification of Letters Patent.

Patented Dec. 3, 1907.

Application filed April 12, 1907. Serial No. 367,750.

To all whom it may concern:

Be it known that I, EDWARD H. PALMER, a citizen of the United States, residing at Detroit, county of Wayne, State of Michigan, have invented a certain new and useful Improvement in Combining and Mixing Tubes, and declare the following to be a full, clear, and exact description of the same, such as will enable others skilled in the art to which

it pertains to make and use the same, reference being had to the accompanying drawings, which form a part of this specification.

My invention relates to a combining and mixing tube, and the object of my improvements is to provide an improved tube adapted to be used with an inverted incandescent mantle lamp of that kind in which an inflammable liquid is vaporized and mixed with air and burned to heat the mantle. By my improvements, I do away with the noise usually produced by the rushing gases, and thoroughly mix the vapor and air.

In the drawings:—Figure 1, is an elevation of a lamp of the inverted incandescent mantle type to which my invention is applied. Fig. 2, is a sectional view of a part of said lamp with a mixing tube embodying my invention secured thereto. Fig. 3, is an end view of said mixing tube. Fig. 4, is an elevation of the interior tube and tip.

L is the sheet metal portion of the lamp, and g is the globe secured to the lower end of the sheet metal portion L.

m is the mantle.

C is the supply tube for gas or inflammable fluid, as gasoline.

A is the delivery nozzle, and B is the needle valve for controlling the flow of such fluid or gas. The nozzle A is convex inward forming a receptacle, around its inner edge, for any dirt that may fall on it.

a indicates folds of gauze which is placed as a strainer in the tube C.

D is an air chamber open to the atmosphere, into which chamber the nozzle A extends.

E is the mixing tube proper, and G indicates an enlarged lower portion of the tube E. The bore of the tube E is axially in line with the nozzle A, so that vapor delivered from said nozzle is projected into the tube E, carrying with it air from the chamber D.

F is a tube coaxial with the tube E, its upper end screwing into the lower end of the smaller part of the tube E. The inner tube F extends into the enlargement G of the tube

E, coaxial therewith, leaving a space around it between its outer wall and the inner wall of the enlargement G.

f are holes through the inner tube F communicating with the upper portion of the space between the inner wall of the enlargement G and the tube F, at the upper end thereof.

H is a tip screwed into the lower end of the inner tube F. The tip F has a small coaxial cavity I formed in it from its upper end and is provided with slots or saw kerfs h crossing each other and extending in from its lower end and communicating with the cavity I. The lower end of the tip H is enlarged, so as to nearly, but not quite, fill the lower end of the tube EG. An annular space J is left between the lower end of the tip H and the end of the tube EG.

75

R is a metal ferrule placed over the end of the tip F to separate the exits from the slots h from the annular space J.

The operation of the above described device is as follows:—If fluid is used it is vaporized and issues in a jet of vapor or gas from the nozzle A, which projects the vapor into the tube E, carrying with it a proper amount of air for combustion, and the air and vapor are thoroughly mixed in said tube, part of the air and vapor passing through the holes f and issuing largely through the annular space J, and a part passing downward and through the cavity I and saw kerfs h, and together with the portion issuing through the annular space J, burning adjacent to the lower end of the mixing tube EG, so as to heat the mantle M. By this construction, the stream of vapor and air is divided and its velocity gradually diminished, so that it makes no noise, while at the same time the vapor and air is completely and properly mixed.

The lamp may be lighted by inserting the torch in the chamber D. The flame will be carried down through the tube EG, and the mixture will continue to burn at the end of said tube.

The tip A has a small passage at its center, forming its bore, and is concave outward to facilitate the insertion of a wire, to clean out the bore of said tip.

What I claim is:—

1. In a device of the kind described, the combination of concentric tubes spaced to produce an annular chamber, passages through the inner tube, a tip provided with a

cross slot inserted in the end of the inner tube and forming between itself and the outer tube an annular delivery passage for said annular chamber, said cross slot forming 5 an inner passage surrounded by said annular passage, substantially as described.

2. In a device of the kind described, the combination of an inner and outer tube arranged to form an intermediate chamber, 10 holes through said inner tube leading to said chamber, the lower end of said inner tube being arranged to form an exit between it and the outer tube, and a slot *h* in the lower end of said inner tube communicating with the 15 interior thereof and with said intermediate chamber.

3. In a device of the kind described, the combination of an inner and outer tube arranged to form an intermediate chamber, 20 holes through said inner tube to said chamber, the lower end of said inner tube being arranged to form an exit between it and the outer tube, a slot *h* in the lower end of said

inner tube connecting with the interior thereof and with said intermediate chamber, and a 25 ferrule over the end of said inner tube.

4. In a device of the kind described, concentric tubes spaced to produce an annular chamber, the inner tube being provided with passages communicating between the interior thereof and said annular chamber, a tip 30 of larger diameter than the interior tube and provided with a cross slot, said tip being inserted in the end of the inner tube and forming between itself and the outer tube an 35 annular passage, a ferrule surrounding the tip and dividing the said annular passage from the passage produced by said slot, substantially as described.

In testimony whereof, I sign this specification in the presence of two witnesses.

EDWARD H. PALMER.
